CARTRIDGE BELT FILLING MACHINE

John H. Woodberry, United States Army,
Metuchen, N. J.

Application November 13, 1941, Serial No. 418,991

9 Claims. (Cl. 86—48)

(Granted under the act of March 3, 1883, as
amended April 30, 1928; 370 O. G. 757)

The invention described herein may be manufactured and used by or for the Government for governmental purposes, without the payment to me of any royalty thereon.

This invention relates to a machine for loading cartridge belts, and in particular to an element which facilitates opening a belt for insertion of a cartridge. The novel element in its preferred form comprises a pivoted member with an oscillating or shuttle action actuated by the normal motions of belt and cartridge respectively in the loading operation.

In the known types of belt loaders, as shown for instance in U. S. Patent No. 660,244, a pair of needles is employed to initiate the separation of the sides of a cartridge belt preparatory to insertion of the cartridge. Considerable difficulty has been experienced with the operation of needles. They break and get out of adjustment. As a result, the present machines operate very unsatisfactorily. Considerable time is lost by operators, and skilled mechanics have to supervise the operations in order to keep the needles properly adjusted.

It is therefore an object of the invention to produce a belt opener for a loading machine which shall be sturdy of construction as well as positive in action and which will obviate the use of needles for belt opening purposes.

The specific nature of the invention as well as other objects and advantages thereof will clearly appear from a description of a preferred embodiment as shown in the accompanying drawing in which:

Figure 1 is a top plan view of a conventional belt loading machine with the novel belt opener or shuttle in place.

Figure 2 is a view in perspective of the shuttle.
Figure 3 is a top plan view of the shuttle, and
Figure 4 is a front view of the shuttle.

Referring to the drawing by characters of reference, there is shown in Figure 1 a belt-loading machine of known construction having a bed plate 1, and a swinging arm 2 carrying a star wheel 3 with troughs 4 to back up the cartridge pockets 5 in the belt. A magazine 6 holds the cartridges 7 and a pusher member 7' advances the cartridges into the belt when the handle 9 is turned. Another star wheel similar to 3 is located beneath the belt to cooperate with wheel 3 in backing up the belt pocket 5 and is connected with the driving action so as to advance the belt at the proper time.

For initiating opening of the pockets 5 in the belt, the shuttle 10 is provided. This is pivoted

at 11 between the bed plate 1 and jutting arm 12 fixed to the bed plate. In the form shown by way of example the shuttle has two disk faces 13 and 14 separated by a distance approximately 5 equal to the thickness of the belt to be loaded when the latter is empty and collapsed. The faces 13, 14 are joined only by a small bridge of material 8 surrounding the pivot hole 15 and by the finger or blade 16. The latter has a forward edge 17 generally axe-like in shape, a broadening rounded inner edge 18 and a flat outer edge 19 on the general line of the periphery of the disks. A rounded channel 20 is formed in the outer edge 19 and at the forward edge of this channel is a somewhat deeper indentation 21. The edge 17 is shown as midway between the faces 13, 14 but may have other intermediate positions depending upon the opening it is intended to engage.

20 Opposite the base of the finger, the disks 13, 14 are recessed as at 22 and 23, respectively. The inner edges of the peripheries of disks 13, 14 are rounded as shown at 24, 25 to provide easy guides for reception of the belt. An abrupt shoulder 26 on the upper disk 13 forms a stop for the rotating shuttle, although any convenient form of stop may be employed.

The functions of the various features of structure 30 embodied in the shuttle are best described by following a cycle of operations in the belt-loading machine. Figure 1 shows the position of the various units with a particular cartridge 27 in position for its first advance toward the belt pocket 5 under the urging of the pusher member 7'. As the cartridge advances, the indentation 21 receives the bullet point and gives it a final guarantee of alignment in the direction of the belt pocket 5. The shuttle, which is simply suspended at 11 for free oscillation, is urged in a counterclockwise sense by the advancing cartridge 27. The axe-like edge 17 which enters between the collapsed sides of the belt pocket 5 accurately because of the fixed relation the edge 40 17 bears to the disks 13, 14 guiding the belt, commences the opening of the pocket and guides the bullet point within. Continued rotation of the shuttle thereafter removes the indentation 21 from the path of the advancing bullet point, the 45 side of the bullet being at this stage accommodated in rounded channel 20. As is well known in machines of this type, the cartridge is advanced into the belt in two stages, only the narrow, forward portion being inserted in the first 50 stage. For this reason both the shuttle finger 55

16 and the cartridge can be accommodated at this stage.

When pusher member 1' has advanced to the limit of its motion, the lower star wheel (not shown) advances the belt and the pocket 5 carries with it the finger 16 in a clockwise direction and ejects it. The finger 16 then comes to rest when the indentation 21 contacts the succeeding cartridge which is already in position for the stroke of the pusher.

The stop 26 has no function during the loading process, but is merely provided to guarantee that the shuttle finger 16 will not accidentally progress so far in a counterclockwise direction when no belt is in the machine that its edge 17 will not be engaged by an incoming belt for positioning under the cartridge tip. As a practical matter, no stop is necessary for restraining the shuttle in its clockwise motion, this function being performed by the awaiting cartridge, there being, in general, no break in the continuity of the supply of cartridges from the magazine. However, an additional stop for the shuttle slightly beyond the position of its engagement with the bullet point may be provided.

The recesses 22 and 23 are provided to furnish clearance for the edge of the cartridge belt as the finger 16 is inserted into the pocket 5.

I claim:

1. In a machine for loading cartridges in the spaced pockets of a two-ply belt said machine having a cartridge loading station, means intermittently feeding said belt past said station serially positioning said pockets to receive a cartridge, means delivering cartridges to said station and means for advancing and inserting cartridges singly into said pockets, the combination of a belt opening device comprising a pocket opening finger pivoted on the cartridge receiving side of said belt for rotation into and out of a belt pocket in cartridge receiving position, means on said finger for engagement with a cartridge being advanced by said advancing means to rotate said finger in pocket opening direction and a second means on said finger for engagement with said belt being fed by said belt feeding means to rotate said finger in the opposite direction.

2. In a machine for loading cartridges in the spaced pockets of a two-ply belt, said machine having a cartridge loading station, means intermittently feeding said belt past said station serially positioning said pockets to receive a cartridge, means delivering cartridges to said station and means for advancing and inserting cartridges singly into said pockets, the combination of a belt opening device comprising a pocket opening finger pivoted on the cartridge receiving side of said belt for rotation in the plane of said belt into and out of a belt pocket in cartridge receiving position, and means on said finger for engagement with a cartridge being advanced by said advancing means to rotate said finger in pocket opening direction and a second means on said finger for engagement with said belt being fed by said belt feeding means to rotate said finger in the opposite direction.

3. In a machine for loading cartridges in the spaced pockets of a two-ply belt, said machine having a cartridge loading station, means intermittently feeding said belt past said station serially positioning said pockets to receive a cartridge, means delivering cartridges to said station and means for advancing and inserting cartridges singly into said pockets, the combination of a belt opening device comprising a pocket opening

finger pivoted on the cartridge receiving side of said belt for rotation into and out of a belt pocket in cartridge receiving position, said finger having a generally arcuate body portion terminating in an axe-like pocket entering edge, said body broadening in the direction of said entering edge, means on said finger for engagement with a cartridge being advanced by said advancing means to rotate said finger in pocket opening direction and a second means on said finger for engagement with said belt being fed by said belt feeding means to rotate said finger in the opposite direction.

4. In a machine as defined in claim 3, the combination of a belt opening device as defined in claim 3 in which said means on said pocket opening finger for engagement with a cartridge being advanced comprises a rounded channel on the face of said finger adjacent the cartridges being advanced.

5. In a machine as defined in claim 3, the combination of a belt opening device as defined in claim 3 in which said means on said pocket opening finger for engagement with a cartridge being advanced comprises a rounded channel on the face of said finger adjacent the cartridges being loaded, said channel terminating in a somewhat deeper indentation at the end of said channel adjacent said pocket entering edge.

6. In a machine for loading cartridges in the spaced pockets of a two-ply belt, said machine having a cartridge loading station, means intermittently feeding said belt past said station serially positioning said pockets to receive a cartridge, means delivering cartridges to said station and means for advancing and inserting cartridges singly into said pockets, the combination of a belt opening device comprising a pocket opening finger pivoted on the cartridge receiving side of said belt for rotation into and out of a belt pocket in cartridge receiving position, a pair of spaced plate members guidingly embracing said belt and carried by said finger, means on said finger for engagement with a cartridge being advanced by said advancing means to rotate said finger in pocket opening direction and a second means on said finger for engagement with said belt being fed by said belt feeding means to rotate said finger in the opposite direction.

7. In a machine for loading cartridges in the spaced pockets of a two-ply belt, said machine having a cartridge loading station, means intermittently feeding said belt past said station serially positioning said pockets to receive a cartridge, means delivering cartridges to said station and means for advancing and inserting cartridges singly into said pockets, the combination of a belt opening device comprising a pocket opening finger pivoted on the cartridge receiving side of said belt for rotation into and out of a belt pocket in cartridge receiving position, a pair of spaced plate members guidingly embracing said belt, means on said finger for engagement with a cartridge being advanced by said advancing means to rotate said finger in pocket opening direction and a second means on said finger for engagement with said belt being fed by said belt feeding means to rotate said finger in the opposite direction.

8. In a machine for loading cartridges in the spaced pockets of a two-ply belt, said machine having a cartridge loading station, means intermittently feeding said belt past said station serially positioning said pockets to receive a cartridge, means delivering cartridges to said sta-

tion and means for advancing and inserting cartridges singly into said pockets, the combination of a belt opening device comprising a pocket opening finger pivoted on the cartridge receiving side of said belt for rotation in the plane of said belt into and out of a belt pocket in cartridge receiving position, and means on said finger for engagement with a cartridge being advanced by said advancing means to rotate said finger in pocket opening direction, a second means on said finger for engagement with said belt being fed by said belt feeding means to rotate said finger in the opposite direction, a stop member carried by said

finger and means carried by said machine engageable with said stop member to prevent said finger from returning in said opposite direction beyond the line of advancement of said cartridges.

5 9. In a machine as defined in claim 6, a combination of a belt opening device as defined in claim 6 in which one of said plate members is provided with a stop member and means carried by said machine engageable with said stop member to prevent said finger from returning in said opposite direction beyond the line of advancement of said cartridges.

10 JOHN H. WOODBERRY.
